UNITED STATES PATENT OFFICE.

BENJAMIN J. COLLINS, OF SUPPLY, OKLAHOMA.

CALCULATING MACHINE.

1,402,572.

Specification of Letters Patent. Patented Jan. 3, 1922.

Application filed May 13, 1919. Serial No. 296,723.

To all whom it may concern:

Be it known that I, BENJAMIN J. COLLINS, a citizen of the United States, residing at Supply, in the county of Woodward and 5 State of Oklahoma, have invented certain new and useful Improvements in Calculating Machines, of which the following is a specification.

My invention relates to improvements in 10 calculating machines, and among the objects of the invention is to provide a simple, compact and accurate machine of this character which is reliable in operation and not likely to get out of order.

Important features of the invention reside 15 in a price sheet and one or more rotary cylinders bearing tables for use in conjunction with said price sheet in calculating the prices for different quantities of merchandise.

Other objects of the invention will hereinafter appear, and in order that said invention may be fully understood, reference will now be made to the accompanying 25 drawings, in which:

Fig. 1 is a perspective view of the machine.

Fig. 2 is a vertical cross section on line II—II of Fig. 5.

Fig. 3 is an elevation of one of the cylinders with a table in position thereon.

Fig. 4 is an enlarged, fragmentary cross section on line IV—IV of Fig. 3.

Fig. 5 is a vertical longitudinal section 35 on line V—V of Fig. 2.

In carrying out the invention I employ a suitable case 1 to the interior of which access may be had through a door 3, secured at its upper end to the case 1 by a hinge 40 5 and provided at its lower end with a catch 7 for securing said door in closed position.

10 designates a shaft extending longitudinally through the case 1 and removably secured to the ends of the latter by suitable means, such as nuts 12.

14, 16, 18, and 20 designate four concentric cylinders mounted upon the shaft 10 and provided with peripheral sight-openings 22, 24, 26, and 28, respectively, adapted to register with a sight-opening 30 in the upper portion of the case 1. Said sight-opening 30 is closed by a plate of glass 32 or other transparent material to exclude dust 55 and other foreign matter from passing through the sight openings into the case 1.

Tables 34, 36, 38 and 40 are removably secured to the peripheries of the cylinders 14, 16, 18 and 20, respectively, and are adapted to coact with a stationary price 60 sheet 42 in making calculations. As it may be desirable to change the tables from time to time the tables 34 to 40 inclusive, are removably secured to their respective cylinders by suitable means such as buttons 44 65 rotatively mounted on the cylinders and provided at their outer ends with lips 46 (Fig. 4), which when turned in one direction pass freely through eyelets 48 in the tables and when turned in an opposite direction overlap the margins of the eyelets and reliably hold the tables in position. The price sheet 42 is removably held in place by flanges 50 secured to the case 1 immediately beneath the sight-opening 30. 70 75

Concentric sleeves 52, 54, 56 and 58 are fixed to one end of the cylinders 14, 16, 18 and 20 (Fig. 5), and provided with fixedly-mounted pinions 60, 62, 64, and 66, respectively. Segmental gears 68, 70, 72, and 74 80 intermesh with the pinions 60, 62, 64 and 66 respectively, and are removably mounted upon a stub shaft 76 fixed to one end of the case 1.

The segmental gears 68, 70, 72 and 74 are 85 independently actuated by levers 78, 80, 82 and 84 provided with handles 86, 88, 89 and 90, respectively. The levers 78, 80, 82, and 84 extend through slots 92, 94, 96 and 98 in the case 1 and are normally held in contact 90 with the upper ends of said slots by coil springs 100, 102, 104 and 106, respectively, connected to the levers and the case as disclosed on Fig. 2.

When the parts are in normal position as disclosed by Fig. 2, the sight-openings in the respective cylinders register with the sight-opening 30 in the case 1, but should one of the cylinders be actuated by pulling downwardly upon its respective handle said 100 cylinder will rotate and carry the numbers on its table past the sight opening in the remaining cylinders and in the case 1.

108 designates an indicator consisting of a taut wire or other suitable element extending longitudinally of the sight-opening 30 to indicate where the cylinders should be stopped when actuated through the medium of their respective handles. 105

The tables and the price sheet consist, 110 preferably, of white celluloid sheets with black numerals printed thereon, so that the

latter can be easily read as they appear at the sight-openings. The price sheet 42 is divided into spaces by longitudinal lines 114 and transverse lines 116 and all or any number of said spaces may bear numerals indicating the different prices at which merchandise is to be sold.

The tables on the cylinders are divided into spaces by intersecting lines 118 and 120 and all or any number of said spaces may contain numerals indicating the cost of different quantities of merchandise. The lines 120 are spaced apart to register with the lines 116 on the price sheet 42. If the merchandise is to be sold by the yard the column 124 at the left of each table contains numerals indicating yards, one quarter, one half, and three quarters of a yard, while the two adjoining columns 126 and 128 contain numerals indicating still smaller fractions than found in said column 124. In order that the numerals indicating the full yards in column 124 may be quickly found, said numerals are displayed in relatively large type and the lines 120 running through said numerals are doubled as indicated at 130, 132 and 134.

Assuming now, that one yard and three inches of lace is to be sold at 9¢ per yard the operator quickly ascertains the cost of such piece of lace by pulling downwardly on the handle of the proper cylinder to rotate the same until the numeral 1 in the vertical column 124 and the adjacent numeral 3 in the vertical column 126 pass above the indicator 108, whereupon the cylinder is stopped with the line 131 registering with said indicator 108. The operator then follows the double line 130 to the right with his eye until the column containing the numeral 9 is reached which column registers with the column containing the numeral 9 on the price sheet 42. The correct price is then ascertained by dropping to the numeral 9 immediately beneath said numeral 9 and located in the transverse column containing

the numeral 3 above-mentioned. Thus the cost for a piece of lace one yard and three inches long is ten cents.

Any number of cylinders may be employed, and by arranging said cylinders concentrically maximum capacity in a minimum space is obtained. Should it be desirable to change the tables on the cylinders for different lines of business, said cylinders can be readily removed from the case 1 by opening the door 3 and removing the shaft 10.

While I have shown the preferred embodiment of the present invention, I reserve the right to make such changes in the construction, combination and arrangement of parts, as properly fall within the spirit and scope of the claims.

Having thus described my invention, what I claim and desire to secure by Letters Patent, is:

In a machine of the character described, a case having a sight-opening therein, a table on said case adjacent the sight-opening, a shaft in said case, concentric cylinders mounted on said shaft and having sight openings for registration with the sight opening in the case, tables on said cylinders for display at the sight openings and adapted to coact with the first-mentioned table in making calculations, an indicator extending longitudinally of the sight opening in the case, for the purpose specified, means for rotating said cylinders independently of each other, sleeves to the cylinders, pinions fixed to said sleeves, gears intermeshing with said pinions, levers extending through the case and fixed to said gears to actuate the same, and springs to restore said levers to initial position.

In testimony whereof I affix my signature, in the presence of two witnesses.

BENJAMIN J. COLLINS.
